UNITED STATES PATENT OFFICE.

FREDERICK D. ALLEN, OF BOSTON, MASSACHUSETTS, ASSIGNOR TO ALLEN, LANE & CO., OF SAME PLACE.

DESIGN FOR A HORSE-BLANKET.

SPECIFICATION forming part of Design No. 12,060, dated December 14, 1880.

Application filed October 22, 1880. Term of patent 7 years.

To all whom it may concern:

Be it known that I, FREDERICK D. ALLEN, a citizen of the United States, residing at Boston, in the county of Suffolk and State of 5 Massachusetts, have invented and produced a new and original Design for Horse-Blankets, of which the following is a specification.

The drawing represents a portion of a horse-blanket sufficient to illustrate my design.

10 My design consists, substantially, of a body formed of crossed bars having an edge or border of Greek pattern.

x is the body or main portion of the blanket, and *y* is the border or edge.

15 The design upon the body consists of the broad cross-bars *A*, provided with the filling-lines *a* and shaded by the block-lines *B*. The border, which is separated by the block-line *c* from the body, is of Greek pattern, *D*, and has

20 filling-lines *d*, and is shaded by the block-line *E*. A bar, *F*, skirts the outer edge of the border.

The block-lines *B*, *c*, and *E* are not abso-

lutely necessary to the design, nor is the bar *F*. The essential feature is a body consisting 25 of crossed bars, crossed at right or other angles, flanked by a border of Greek pattern.

Having thus fully described my design, what I claim, and desire to secure by Letters Patent, is—

30 1. The design for a horse-blanket, consisting of the body formed of bars *A*, crossed at any angle, and the border of Greek pattern, *D*, as shown.

2. The design for a horse-blanket, consisting of the cross-bars *A*, dividing-line *c*, Greek border *D*, and marginal bar *F*, as shown.

3. The design for a horse-blanket, consisting of the cross-bars *A*, having filling-lines *a* and shade-lines *B*, dividing-line *c*, and Greek 40 border *D*, having similar filling and shadelines, and bar *F*, as shown.

FREDERICK D. ALLEN.
